UNITED STATES PATENT OFFICE.

HENRY McMASTER, OF DETROIT, MICHIGAN.

CEMENT POST.

SPECIFICATION forming part of Letters Patent No. 744,976, dated November 24, 1903.

Application filed September 23, 1903. Serial No. 174,247. (No model.)

To all whom it may concern:

Be it known that I, HENRY McMASTER, a citizen of the United States of America, residing at Detroit, in the county of Wayne and State of Michigan, have invented certain new and useful Improvements in Cement Posts, of which the following is a specification, reference being had therein to the accompanying drawings.

10 This invention relates more specifically to an improvement in cement posts adapted for use as fence-posts, hitching-posts, and the like; and the invention has for its particular object to adapt the post to all styles and makes 15 of fences, such as wire fences, wooden board fences, fences with detachable panels, &c.

To this end my invention consists in a particular and novel construction whereby the desired object is obtained in a simple and inexpensive manner, which permits any farmer or person of ordinary skill to manufacture the same without the use of any special tools and from material which is easily procurable, all as 25 more fully hereinafter described, and shown in the accompanying drawings, in which—

Figure 1 is an elevation of a fence-post embodying my invention. Fig. 2 is a vertical section thereof; and Fig. 3 is a horizontal cross-section substantially on line xx , Figs. 30 1 and 2.

As shown in the drawings, A represents the cement body of the post, which may be of any desired form and dimensions. B is a piece of band-iron, and C is a stick of wood, preferably cut out of a piece of board.

Both the band-iron and the wood are embedded in the upper portion of the body of the post in such manner that on those portions of the cement body to which the fence 40 or top wires, boards, &c., must be fastened the band-iron is exposed on the face of the post, while the wooden stick forms a backing for these exposed portions.

For building a wire or board fence the band-iron would have to be exposed for the whole 45 height of the fence upon the face of the post, as shown in Fig. 1, and this entire portion a should be backed by the block of wood, to which the band-iron may be secured by a few 50 nails or otherwise to hold it in position thereon. Similarly, a portion b of the band-iron may be exposed at the top of the post, the

upper end of the stick extending up beneath to form a backing for it.

I preferably have the band-iron of sufficient length to extend around the whole block of wood, with the portion c thereof arranged at an angle to the axis of the post so as to form an angular brace within the body of the cement post. I also prefer to use band-iron of greater width than the thickness of the block of wood, so that projecting shoulders d are formed where the strip of wood lies against the band-iron.

A cement post of this construction is of great strength, especially in the direction in which strength is needed, it costs but little more than the cost of the cement, and its construction is within the capacity of any person of ordinary skill. Aside from these advantages my cement post offers facility for the construction of fences of any style or make necessitating the use of nails, staples, screws, or other modes of fastening, since nails or staples may be readily driven anywhere through the exposed portions of the band-iron into the wood, or, if necessary, holes may be punched through the band-iron for the purpose, (before the post is molded,) and it will readily be seen that a much stronger fastening is obtained than by the use of wood alone, while at the same time the band-iron protects the wood and the cement post from injury through various causes well understood by those having experience with the various styles of cement fence-posts in present use.

An additional advantage is that my fence-post presents a ready means for fastening a fence-wire, barbed wire, or fence-board on top of the post itself or adapting it for a convenient hitching-post by fastening a ring with a staple in the top thereof.

It is obvious that instead of band-iron strips of tin, galvanized iron, or other equivalent material may be used, and this and other obvious modifications are included within the scope of my patent.

Having thus fully described my invention, what I claim is—

1. A post composed of a body portion of cement, a strip of sheet metal embedded therein and having a portion or portions thereof exposed on the surface of the post and another

portion angularly disposed within said body and a block of wood disposed within the body portion and forming a backing for the exposed portions of the metal strip.

5 2. A cement post having a strip or band of metal embedded therein in the longitudinal direction thereof, parts or portions of said strip being exposed upon the face of the posts and a strip of wood within the post and forming a backing for the exposed portion of said strip.

10 3. A fence-post composed of a body portion of cement, a strip of sheet metal embedded therein and having portions thereof on one side and on top of the post exposed flush with the surface thereof and a block of wood em-

bedded within the body of cement and forming a backing for the exposed portions of the metal strip.

15 4. A cement fence-post having embedded in one side of its overground portion a wooden strip having a sheet-metal strip secured thereto covering the exposed edges of the wooden strip and extending within the post free of the wooden strip.

20 25 In testimony whereof I affix my signature in presence of two witnesses.

HENRY McMaster.
